METHOD OF AND APPARATUS FOR HEAT-TREATING AND BURNING PULVERIZED MATERIALS

David Dalin, Sodertalje, Sweden

Application April 15, 1946, Serial No. 662,111
In Sweden June 17, 1944

4 Claims. (Cl. 122—235)

1

This invention relates to improvements in the method and apparatus for burning and heat treating powdered or pulverized materials in furnaces or ovens. More particularly, this invention concerns the regulation and control of furnace temperatures generated by the combustion of pulverized fuels and the maintenance in the furnace of a uniform temperature most suitable for the combustion of the fuel.

Such fuels as powdered or pulverized coal, charcoal, and peat burn at an extremely rapid rate when injected along with air into the combustion chamber of a furnace, and the excessively high temperatures generated as a result of such combustion are responsible for what is commonly known as sintering of the fuel. When sintering occurs combustion of the fuel is interfered with and rendered incomplete so that efficient combustion and liberation of all of the heat energy contained in the powdered fuel is impossible.

The primary object of this invention is to maintain combustion chambers in which pulverized fuels are burned at a uniform temperature of a value below the sintering temperature of the fuel by leading away and utilizing for useful purposes the excessive heat generated during the combustion process so as to prevent sintering of the fuel but to assure combustion of the fuel at temperatures most suitable from the standpoint of rapid and complete combustion.

Past methods for controlling combustion temperatures of such powdered fuels as pulverized coal, charcoal, and peat relied upon admitting excessive amounts of air into the combustion chamber, or the circulation of spent combustion gases therethrough.

While such practice affords a degree of control over the temperatures in the combustion chamber and acts to limit sintering of the materials being burned, it is nevertheless unsatisfactory for the reason that the large excesses of air and/or spent combustion gases circulated through the combustion chamber interfere with rapid and complete combustion and efficiency suffers as a result thereof. Moreover, excesses of air and combustion gases must be forcefully circulated through the combustion chamber by means of pumps or blowers which require the expenditure of considerable power for their operation.

Hence, it is another object of this invention to provide for efficient burning of powdered fuels and heating of other materials such as pulverized ores by a method which avoids excesses of air and which employs fluid cooled ducts positioned to be impinged by combustion gases in the combustion

chamber to usefully absorb excess heat from the burning or heated material.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiment of the invention constructed according to the best modes so far devised for the practical application of the principles thereof, and in which:

Figure 1 is a somewhat diagrammatic view through a furnace in which the combustion process of this invention may be carried out;

20 Figure 2 is a cross sectional view through the combustion chamber of the furnace taken along the plane of the line 2—2 of Figure 1;

15 Figures 3, 3a, and 3b are diagrammatic views illustrating various ways in which the fluid cooled ducts may be shielded to prevent direct contact between the same and the material being treated;

25 Figure 4 is a more or less diagrammatic longitudinal sectional view through a furnace of slightly different construction;

30 Figure 5 is a cross sectional view taken through Figure 4 on the plane of the line 5—5;

35 Figure 6 is a diagrammatic longitudinal sectional view of still another form of furnace by which the method of this invention may be practiced; and

Figure 7 is a sectional view taken through Figure 6 on the plane of the line 7—7.

In the method of this invention, pulverized fuel such as coal, charcoal, or peat is injected together with air required for combustion of the fuel into the combustion chamber of a furnace to be ignited upon its entry thereto and caused to flow along a defined path through the combustion chamber.

40 Inasmuch as the pulverized fuel burns at an extremely rapid rate, combustion temperatures in the combustion chamber rise to excessively high degrees at which sintering of the fuel particles takes place. When sintering occurs complete combustion of the fuel particles is impossible and much heat energy is wasted.

45 The method of this invention seeks to obtain all of the heat energy available in powdered fuels by controlled combustion thereof to preclude sintering of the fuel, and so that combustion is carried on under the most suitable conditions.

In order to control the combustion temperature of the fuel, the excessively hot combustion gases with burning fuel particles entrained therein are caused to circulate through the combustion chamber past heat absorbing surfaces which remove excessive heat from the fuel particles and lower their temperature to values below the sintering temperature of the fuel being burned.

The cooling surfaces, however, are provided by ducts through which a fluid heat absorbing medium is circulated, and by which the excess heat of the burning fuel particles is led away from the combustion chamber to be utilized for useful purposes.

In the apparatus more or less diagrammatically shown in Figure 1 the furnace in which the method of this invention may be carried out is generally designated by the numeral 5 and is shown provided with an upright substantially cylindrical combustion chamber 6.

Air having pulverized fuel entrained therein is injected into the combustion chamber under pressure through a nozzle 7 opening tangentially through the side wall 8 of the chamber near the top wall 9 thereof. Sufficient air is employed to act as a carrier or vehicle for the pulverized fuel injected into the combustion chamber and to provide all the primary air needed for combustion.

The air and entrained pulverized fuel entering the combustion chamber is caused to sweep along the side wall of the combustion chamber adjacent to the inlet nozzle 7. This area of the combustion chamber, designated 10, having been pre-heated in any suitable manner such as by directing a flame thereagainst, serves to ignite the incoming combustible material borne along with the air, and the tangential direction of injection causes the combustion gases together with the burning particles of fuel to swirl spirally around the interior of the combustion chamber toward the bottom 11 thereof.

Secondary air is also injected into the combustion chamber through nozzles 1' and 1'' opening through the side wall of the chamber to mix with the combustion gases and enable complete combustion of the burning fuel particles entrained therein.

As indicated in Figure 1, the combustion gases and entrained burning fuel particles travel completely around the interior of the combustion chamber a number of times before discharge through a substantially centrally disposed annular outlet port 12 in the bottom wall 11 of the chamber.

Excessive heat generated by combustion of the material traveling through the combustion chamber may be partly carried away by means of a central cooling shaft generally designated 13. The cooling shaft 13 comprises a cylindrical shell 14 open at its ends and mounted in an upright fashion in the combustion chamber on the central axis thereof.

The walls of the cooling shaft are preferably of metal so as to readily absorb heat from the combustion gases and burning particles passing over its exterior exposed within the combustion chamber, and such absorbed heat is carried away by air circulating upwardly through the open ends of the shell. The cooling effect obviously may be increased by forcefully circulating cooling air upwardly through the shaft if desired.

In the furnace shown, the cooling shaft is mounted for rotation on its upright axis in suitable bearings 15 carried by the top wall 9 of the

combustion chamber, and an intermediate bottom wall 16 spaced beneath the bottom wall 11. A thrust bearing 17 confined between the upper bearing 15 and an overhanging flange 18 on the shaft serves to suspend the shaft inside the furnace, and rotation of the shaft may be effected through a power driven bevel pinion 19 meshing with a bevel gear 20 carried by the lower end of the shaft.

The discharge opening 12 in the bottom wall 11 of the combustion chamber surrounds the cooling shaft and also provides for the discharge of ash accumulated on the bottom wall of the combustion chamber. Such ash is collected and discharged through the opening 12 to fall onto the intermediate wall 15 by arms 21 fixed on the exterior of the rotatable cooling shaft to scrape across the bottom wall 11.

The combustion gases discharging from the chamber likewise enter the space between the walls 11 and 15, but are lead into a dust separator generally designated 22 through a port 23 in the side wall of the furnace communicating with the space between the walls 11 and 16.

Any ash which deposits upon the intermediate wall 16 is collected by a second set of scraper arms 24 on the cooling shaft and conducted through openings 25 in the intermediate wall near the side wall 8 of the furnace to drop onto an extreme bottom wall 26 spaced beneath the intermediate wall 16.

Scraper arms 27 carried by the cooling shaft and arranged to traverse the bottom wall 26 force the collected ash outwardly of the furnace through an annular opening 28 adjacent to and surrounding the exterior of the cooling shaft. It is to be understood, of course, that the ash discharged from the furnace in this manner drops into a suitable ash pit for subsequent removal.

Dust and ash or other solid particles are separated from the combustion gases in the separator 22 and collect in a bin 30 while the combustion gases discharging from the separator are caused to flow through a heat exchange apparatus indicated at 31, and if desired through an additional dust separator indicated at 32 and then to apparatus, not shown, such as a waste heat boiler for further utilization of the heat of the gases.

As stated previously, the cooling shaft 13 provides for a degree of control over the temperature in the combustion chamber 6. Most of the control over the temperature in the combustion chamber, however, is obtained by means of a series of vertical fluid cooled ducts 34.

These ducts are positioned in the combustion chamber to provide heat absorbing and dissipating surfaces in the path of the spirally traveling combustion gases and effect removal of sufficient heat from the interior of the combustion chamber as to preclude sintering of the burning fuel particles.

With relation to the spiral path of the combustion gases and entrained burning fuel particles, it will be seen that the fluid cooled ducts nearest the inlet for the combustion chamber are located directly adjacent to the wall section 9 by which ignition is effected, so that the fuel particles impinge these ducts immediately after being ignited and started on their spiral course through the combustion chamber. The ducts thus exercise a cooling effect on the combustion gases immediately after their ignition, but it is important to note that the ducts are so formed and positioned as to exercise their greatest cool-

ing effect on the hot combustion gases and burning fuel particles entrained therein at the area of greatest heat, with the cooling effect gradually decreasing along the length of the path of the gases so as to exercise the least cooling effect adjacent to the outlet of the combustion chamber.

In this manner cooling of the combustion chamber and the gases flowing therethrough below a temperature most advantageous for efficient combustion of the fuel without sintering thereof is avoided, and a substantially uniform temperature is maintained throughout the entire combustion chamber with said temperature at a value below the sintering temperature of the fuel being burned.

It will be understood, of course, that the temperature most suitable for the complete and efficient combustion of the fuel being burned without sintering of the fuel may be regulated either by regulation of the volume or temperature of the fluid circulated through the ducts. The fluid cooled ducts connect with headers 36 for this purpose and these headers in turn may be connected with a steam drum or the like by which the heat absorbed from the burning materials in the combustion chamber may be utilized for useful purposes.

In the event direct contact of the burning particles with the cooling surfaces provided by the fluid cooled ducts 34 has a tendency to retard combustion, the ducts may be provided with sleeves, such as indicated at 38, 38', and 38" in Figures 3, 3a, and 3b, telescoped over the ducts with their side walls spaced from the exterior of the ducts.

The method of controlling combustion temperatures in the burning of pulverized fuels may also be carried out in a furnace such as that illustrated in Figure 4. This furnace is in many respects similar to that described but the outlet for the combustion chamber is provided by a vertical exhaust duct 40 extending down into the combustion chamber from the top thereof to have its open lower end 41 providing a discharge port for combustion gases spaced a distance above a grate 42 extending across the lower portion of the furnace and defining the bottom of the combustion chamber.

The grate provides for the complete combustion of burning particles of fuel which drop out of suspension at or near the entrance 41 to the exhaust duct 40 for upward travel therethrough. Ports 43 in the conical side walls of the furnace beneath the grate provide for the supply of air to burning material resting on the grate to complete combustion thereof. It is to be understood that the grate is of the type which is movable to permit dropping of the ash into the hopper like conical bottom portion of the furnace in the usual manner.

The exhaust duct 40 is preferably formed of one or more circumferential rings of vertical cooling tubes 45 having their peripheries in engagement with one another as shown in Figure 5 so as to provide a substantially cylindrical cooling surface about which the hot combustion gases traveling through the combustion chamber circulate to be cooled thereby.

Hence, the walls of the exhaust duct 40 cooperate with the fluid cooled ducts 34 inside the combustion chamber to maintain a uniform temperature in the chamber of a value below the sintering temperature of the pulverized fuel being burned.

The combustion gases traveling upwardly

through the exhaust duct 40 may be lead through a heat exchanger such as a waste heat boiler of a superheater 46 having a multitude of ducts 47 disposed therein to be impinged by the hot combustion gases passing through the superheater.

It is to be understood that the ducts 47 have a fluid such as a steam emulsion circulated therethrough and are connected with headers 48 which in turn may be connected with a steam drum or the like.

Dust collecting hoppers 49 arranged beneath the bank of ducts 47 receive the ash which drops out of suspension from the combustion gases passing through the superheater, and to effect further separation of dust and ash the combustion gases discharging from the outlet 50 of the superheater are led into a dust separator 51. Obviously, the hot combustion gases may then be lead to other apparatus where the heat thereof is further utilized.

In the Figure 6 embodiment a substantially rectangular combustion chamber 53 is shown as comprising the major part of a combined oven and boiler. The boiler tubes 54 connect to headers 55 and as in the previous embodiments the tubes or ducts lie in the path of combustion gases traveling horizontally through the combustion chamber toward its outlet 57.

In this embodiment also, powdered fuel together with air for supporting combustion of the fuel are injected together through the inlet 56 into the combustion chamber to be ignited upon its entrance thereto. The boiler tubes 54 likewise exert a cooling influence upon the combustion gases and the burning particles of fuel entrained therein to cool the same and the interior of the combustion chamber to a temperature below the sintering temperature of the fuel.

Dust and ash collecting hoppers 60 are likewise provided beneath the boiler tubes to receive any ash and dust which drops out of suspension during travel of the combustion gases through the chamber.

Referring to Figure 7, it will be seen that the boiler tubes 54, which provide cooling surfaces impinged by the hot combustion gases and entrained burning fuel particles, are arranged with the greatest number thereof adjacent to the inlet 56. These tubes also decrease in number toward the outlet 57 so that throughout the combustion chamber a temperature most suitable for efficient combustion of the fuel is maintained.

In both the Figures 4 and 6 embodiments, it is to be understood that the combustion chamber is provided with openings 7' and 7" for the injection of secondary air as described in connection with the apparatus of Figure 1.

While the method and apparatus has been described as dealing primarily with temperature control in the burning of pulverized fuels such as powdered coal, charcoal, and peat, the method and apparatus is equally as well suited for the heating and melting of the metal content of pulverized ores.

In this latter case it is also highly important that temperatures in excess of the sintering temperature of the ores being treated be avoided so as to assure efficient recovery of the metal content thereof.

From the foregoing description taken in connection with the accompanying drawings, it will be readily apparent to those skilled in the art that the method and apparatus of this invention provide for improved and highly efficient control over combustion temperatures when burning or

heat treating powdered materials, and that such control is effected without waste of the excess heat removed from the materials during their processing.

Those skilled in this art will also readily understand that the term "powdered fuel" encompasses a relatively wide range of particle sizes including what might be more accurately defined as granular or granulated fuel.

What I claim as my invention is:

1. A furnace for burning powdered fuel, comprising: a substantially cylindrical combustion chamber having an outlet adjacent to one end portion thereof; means defining a substantially tangential inlet port in the side of the combustion chamber adjacent to the opposite end portion of the chamber and through which powdered fuel and air required for combustion of the fuel may be injected to burn inside the chamber while travelling in a substantially spiral path through the combustion chamber toward the outlet thereof; and fluid cooled ducts distributed within the combustion chamber away from the walls thereof and spaced from one another to be impinged by combustion gases and burning fuel particles travelling along said spiral path, the distribution and size of the ducts being such that the total surface area thereof diminishes along said path of the combustion gases towards the outlet of the combustion chamber, so that the cooling influence of said ducts upon the burning particles is substantially directly proportional to the temperatures of the particles.

2. A furnace for burning powdered fuel, comprising: an upright substantially cylindrical combustion chamber; an exhaust duct extending down into and substantially axially of the combustion chamber through the top thereof with its lower end opening into the combustion chamber at the lower portion thereof and providing an outlet for said chamber; means on the side of the combustion chamber at its upper portion defining a substantially tangential inlet through which powdered fuel entrained in air required for combustion of the fuel may be injected into said chamber to be ignited upon its entrance thereto and so that the resulting combustion gases and the particles of burning fuel entrained therein travel in a substantially spiral path around the exhaust duct downwardly through the combustion chamber for discharge through the outlet port defined by the lower end of the exhaust duct; and fluid cooled heat absorbing ducts in said combustion chamber for controlling the temperature thereof, said ducts being spaced

from the walls of the combustion chamber and from one another and distributed within the interior thereof to be impinged by combustion gases and burning fuel particles traveling along said spiral path, the distribution and size of the ducts being such that the total surface area thereof diminishes along said path of the combustion gases towards the outlet of the combustion chamber, so that the cooling influence of said ducts upon the burning particles is substantially directly proportional to the temperature of the particles.

3. A furnace as set forth in claim 2 wherein said axial exhaust duct is a cooling unit comprising a group of closely adjacent fluid cooled ducts substantially forming an inner circumferential wall about which the combustion gases and burning fuel particles swirl in their travel along said spiral path.

4. The method of combusting fuel of small particle size which comprises: forcing the fuel together with air required for combustion thereof along a defined path through a combustion chamber with the fuel particles entrained in said air; igniting the fuel as it enters the combustion chamber so that the burning particles and the combustion gases travel along said path; circulating a fluid coolant back and forth across the path of the burning fuel particles and combustion gases in indirect heat exchange relation therewith and in diminishing effectiveness along said path of the burning fuel particles in the direction of gas flow so that the cooling effect of said fluid coolant upon the burning fuel particles is substantially directly proportional to the temperature of the particles.

DAVID DALIN.
